UNITED STATES PATENT OFFICE

EDWARD LLEWELLYN O'NEIL, OF LONDON, ONTARIO, CANADA

KNOCKDOWN SECTIONAL DISPLAY SHELVES

Application filed September 8, 1930. Serial No. 480,541.

My invention relates to improvements in knock-down sectional display shelves, and the object of the invention is to devise metallic shelves which may be built up vertically in any number of sections, to any desired height and which, when knocked-down, will occupy a minimum amount of space for shipment and in which the connections are so formed between the shelves as to leave a free 10 uninterrupted surface for the occupation of the goods upon the uppermost shelf, and it consists essentially of the arrangement and construction of parts as hereinafter more particularly explained by the following 15 specification.

Fig. 1 is a perspective view of my shelves formed in two sections.

Fig. 2 is an enlarged transverse sectional view through my display shelves.

Fig. 3 is a plan view of a fragmentary portion of the uppermost display shelf showing the interlocking connection between the shelf body and the supporting standard.

Fig. 4 is a sectional view on line 4—4 Fig. 25. 3.

Figs. 5 and 6 are perspective details of the interlocking connection between one of the shelves and its supporting standard.

In the drawings like letters of reference 30 indicate corresponding parts in each figure.

1 is a base member provided with a hollow boss 1^x into which fits and is secured a tubular standard 2, such securing connection being preferably formed by a bolt 3 extending through the wall of the boss 1^x and through an open ended slot 3^x formed in the lower end of the standard 2.

4 and 5 are shelf members preferably formed of sheet metal and forming the main 40 member of each shelf section. The members 4 and 5 are provided with orifices 4^x and 5^x corresponding in diameter to the external diameter of the tubular standard 2. The orifices 4^x and 5^x are each provided with radial slots 4° of any desired number and spaced equal distances apart. The metal out of which the slots 4° are formed is stamped down as indicated at 5° to form the engaging member as will hereinafter appear.

50 6 and 7 are sleeve members having an in-

terior diameter corresponding to the external diameter of the standard 2. 8 is a split ring extending around the upper end of each of the sleeve members 6 and 7 and connected thereto by means of projections or pins 8^x fitting into recesses 8°. The rings 8 are provided at their upper ends with annular flanges 9 from which extend cam projections 10; each of such cam projections are inclined and formed by a horizontal lower portion 10^x and a horizontal upper portion 10° at each end of the inclined portion.

It will be noted that the space between the stamped down portions 5° and the slots 4° is slightly greater than the width of the cam portions 10. When the parts are assembled the ring members 8 are sprung into engagement with the upper ends of the sleeves 6 and 7. The cam portions 10 are then passed upwardly through the spaces 70 between the portions 5° so that the portions 10° of the cam engages the lower face of the corresponding shelf member. The sleeve member is then given a rotary movement so as to carry the portion 10° over the portion 5° and the portion 10^x into engagement with the upper face of the portion 5°.

The vertical distance between the upper face of the portion 10° and the lower face of the portion 10^x is slightly greater than the distance between the lower face of the corresponding shelf and the upper face of the portion 5° so that when the cam members 10 are carried into engagement by the rotary movement of the sleeve 6 or 7 the inclined portion of the cam 10 is slightly sprung so as to exert a gripping engagement between such cam members and the shelf. 11 is a pin or projection depending from the shelf so as to limit the turning movement of the 80 sleeve 6 or 7 and the cams carried thereby.

When the sleeves 6 and 7 and shelf members 4 and 5 have been thus connected a tubular standard member 12 is inserted at its upper end in the sleeve 6 and passed, at 95 its lower end, through the orifice 4^x of the shelf 4 into the lower sleeve portion 7, preferably bearing at its lower end upon the upper end of the tubular standard 2. The upper end of the tubular standard 2 and 100

both ends of the member 12 are provided with open ended slots 12^x, securing bolts 13 being provided which pass through the sleeves 6 and 7 so as to engage the slots 12^x as clearly indicated in Fig. 2, thereby positively clamping the parts together.

From this description it will be seen that I have devised a very simple device whereby display shelves may be built up to any height desired by employing any number of shelf sections. Hitherto display shelves of this character have been formed by strips of plate glass between which are inserted glass vases which are fragile and do not hold the shelves firmly in position and, therefore, a set of shelves so built might be easily and inadvertently upset and a great deal of damage done. By my construction I have provided a device which is strong and durable, stable and not liable to damage, which may be easily manufactured and which, when desired, may be knocked-down and compactly packed for shipment.

What I claim as my invention is:

1. Knock-down sheet metal display shelves, comprising a base, a plurality of shelf members having vertically aligned orifices therein, a tubular standard member connected to the base, a sleeve member forming a tubular stem depending from each shelf section concentric with its orifice, a detachable connection between the sleeves and the shelf members, a connecting sleeve inserted at one end in the stem of one shelf member and extending at its opposite end through the orifice of the other shelf member into the stem thereof, and means for locking the sleeves and stems together.

2. Knock-down sheet metal display shelves, comprising a base, a stem extending upwardly from the base, a plurality of shelf members, a tubular stem secured in a depending position to each shelf member, radial cams arranged around the upper end of each stem, and tongue portions carried by each shelf member arranged concentrically around the stem and with which the cams engage when the stem is turned circumferentially.

3. Knock-down sheet metal display shelving, comprising a base, a plurality of shelf members having vertically aligned orifices therein, a tubular standard member connected to the base, a sleeve member forming a tubular stem depending from each shelf section concentric with its orifice, a connecting sleeve inserted at one end in the stem of one shelf member and extending at its opposite end through the orifice of the other shelf member into the stem thereof, and means for locking the sleeves and stems together.

EDWARD LLEWELLYN O'NEIL.
